UNITED STATES PATENT OFFICE.

JOSEPH KINTZ, OF BALLARD VALE, MASSACHUSETTS, ASSIGNOR TO HIMSELF AND THE CRAIGHEAD & KINTZ COMPANY, OF SAME PLACE.

MIRROR-STAND.

SPECIFICATION forming part of Letters Patent No. 409,153, dated August 13, 1889.

Application filed December 11, 1888. Serial No. 293,262. (No model.)

To all whom it may concern:

Be it known that I, JOSEPH KINTZ, of Ballard Vale, in the county of Essex and State of Massachusetts, a citizen of the United States, 5 have invented certain new and useful Improvements in Stands, of which the following is a specification.

My present invention relates to improvements in stands or analogous receptacles containing an interior compartment for dressing-materials, artists' materials, &c., a drawer or tray adapted to be pulled out therefrom, and a hinged top or cover to the said receptacle, connected with the drawer or tray and adapted 15 to be brought automatically into an inclined position by the pulling out thereof, and brought back to its normal or closed position by the returning of the drawer or tray to its place. If the receptacle is to be used for 20 dressing purposes, this top may be provided with a mirror, and I have herein so represented it.

In the accompanying drawings I have shown at Figures 1 and 2, in vertical section, a device 25 embodying my present invention in the form now best known to me, Fig. 1 showing the top in its inclined position or when in use as a dressing-stand, and Fig. 2 showing the top in its horizontal position.

30 In the drawings, A represents the body of the stand or table, which may be of any convenient form.

B represents the top of the stand or table, in which is set a mirror C. The top, which 35 contains the mirror, is so connected with the body of the stand or table—as, for example, by hinges, as indicated at D—that it is capable of being moved from a horizontal position, as shown in Fig. 2, to an inclined position, as

shown in Fig. 1. This top is so connected 40 with a tray E, arranged to slide in and out of the stand or table below the top—as, for example, by means of a link-connection F, pivoted to the top and slide—that when the tray is pulled out the top will stand inclined and 45 when the tray is pushed in will lie flat. In practice I prefer to employ a pair of these links, one at either side of the top. The part E when pulled out will serve as a tray, or, if preferred, it may be provided with a rail, so 50 as to serve as a drawer. The range of outward motion of the sliding part by which the change of position of the top is brought about should be limited to prevent the sliding part from being pulled out too far. A convenient 55 means of doing this is by limiting the range of hinge motion in the hinge D. Sufficient hinge motion should, however, be allowed to permit the links F to assume such a position, substantially as shown in Fig. 1, that they 60 will act to sustain the top in its desired inclined position for use.

I claim—

The combination of a stand having a hinged top, a tray adapted to slide into and out of the 65 stand below the top, and a pivoted link-connection between the tray and top, whereby the top will be raised and supported when the tray is pulled out and be lowered when the tray is pushed in, substantially as described. 70

In testimony whereof I have hereunto subscribed my name this 1st day of December, A. D. 1888.

JOSEPH KINTZ.
